United States Patent Office

Des. 177,328
Patented Apr. 3, 1956

177,328

PLAYING CARD HOLDER

Hugh F. Ireland, South Miami, Fla.

Application November 22, 1955, Serial No. 38,992

Term of patent 14 years

(Cl. D34—13)

FIG. 1

The other side of the playing card holder is a duplicate of the side illustrated.

I claim:

The ornamental design for a playing card holder, as shown and described.
